(57) **CLAIM**

The ornamental design for a magnetic knife holder as shown and described.

DESCRIPTION

1. Magnetic knife holder

1.1 : Perspective

1.2 : Perspective

1.3 : Front

1.4 : Back

1.5 : Left

1.6 : Right

1.7 : Top

1.8 : Bottom

Fig. 1.1 is a front perspective view of the magnetic knife holder, showing my design; fig. 1.2 is a rear perspective view of the magnetic knife holder in fig. 1.1; fig. 1.3 is a front view of the magnetic knife holder in fig. 1.1; fig. 1.4 is a rear view of the magnetic knife holder in fig. 1.1; fig. 1.5 is a left side view of the magnetic knife holder in fig. 1.1; fig. 1.6 is a right side view of the magnetic knife holder in fig.

(Continued)

1.1; fig. 1.7 is a top view of the magnetic knife holder in fig. 1.1; fig. 1.8 is a bottom view of the magnetic knife holder in fig. 1.1.

1 Claim, 8 Drawing Sheets
